STAPLING DEVICE

William G. Pankonin, Chicago, Ill., assignor to
 Ace Fastener Corporation, Chicago, Ill., a corporation of Illinois

Application May 7, 1936, Serial No. 78,301

5 Claims. (Cl. 1—3)

This invention relates to an improvement in stapling machines.

The present invention is a continuation in part of the copending application of William G. Pankonin, applicant herein, Serial No. 585,241, filed January 7, 1932, for Stapling device.

One of the objects of this invention is to provide in a stapling machine an anvil adapted to clench the legs of a staple on the underside of material through which the staple is inserted, in a variety of selected forms.

Another object of the invention is to provide a simplified means for adjustably positioning a staple clenching anvil in selected relation to the staple driving mechanism.

Other objects and advantages reside in certain novel features of the construction, arrangement and combination of parts which will be herein-after more fully described and particularly pointed out in the appended claims, reference being had to the accompanying drawing forming a part of this specification, and in which:

Figure 1 is a view in side elevation, with a part broken away for the sake of clarity, illustrating a stapling machine embodying the present invention;

Figure 2 is an enlarged fragmentary plan view of the anvil and base shown in Figure 1;

Figures 3, 4, 5 and 6 are views in vertical section taken on lines 3—3, 4—4, 5—5 and 6—6, respectively, of Figure 2; and

Figure 7 is an enlarged fragmentary view partly in longitudinal section and partly in side elevation showing an anvil embodying a modified form of the present invention.

Referring to the drawing, it will be seen that the stapling machine comprises generally a base 1, an arm 2 mounted on the base for movement toward and away therefrom, and comprising a magazine for staples, a housing 3 enclosing staple driving mechanism (not shown) mounted on said arm and a plunger 4 carried by said housing and operable to cause staples to be driven from the magazine out through the ejection chute E against the anvil 5. The anvil 5 is adjustably supported on the base 1 beneath the staple driving mechanism.

The construction and operation of the arm 2, housing 3 and plunger 4 is well known to those skilled in the art and does not constitute a part of this invention. In the operation of the device, successively depressing the plunger 4 causes staples to be driven from the magazine out through the ejection chute E. During the driving action the lower edge of the ejection chute E

is depressed and engages between itself and the upper surface of anvil 5 material inserted for the purpose of being stapled and the legs of the staple pass through the material, strike against the anvil 5 and are clenched or deformed as will be hereinafter described.

The base 1 is of customary design except that at the front or anvil supporting end thereof the underside of the base is provided with a cavity or operating space 6 providing clearance room for related parts of the adjustable anvil 5.

The upper surface of anvil 5 has transversely arranged therein a plurality of parallel staple deforming dies or clenching cavities. One set of dies 7 and 7^a is arranged to bend each leg of the staple inwardly toward the other leg to permanently clench the staple. Another set of dies 8 and 8^a is arranged to bend one leg of the staple inwardly and the other leg outwardly. The remaining set of dies 9 and 9^a is arranged to bend both the legs of the staple outwardly. The sets act independently of each other and only one set is operable at a time. To cause a set to be operable, the anvil is movable with respect to the ejection chute E to align a selected set of dies therewith.

To adjustably support the anvil 5 on the base 1, permit its movement longitudinally thereof while maintaining it in proper lateral alignment with the ejection chute E and to position it with a selected set of clenching dies in operative relation with the driving mechanism, the anvil 5 has bearing portions in contact with the upper surface of the base 1 and is provided with tongues or lugs 10 and 10^a which project downwardly through slots 11 and 11^a formed in the base 1. Below the surface of the base 1, within the operating space 6, and extending between the downwardly projecting tongues 10 and 10^a is a spring 12 which is biased so that its central portion bears against the inner or lower surface of the base to cause the anvil by its bearing portion to frictionally engage the upper surface of the base.

The central portion of the anvil may be elevated if desired. With or without the central portion elevated, the slots 11 and 11^a are formed with less width than the front and rear edges of the anvil 5 and the tongues 10 and 10^a are a close but sliding fit within the slots 11 and 11^a and are positioned centrally with respect to the front and rear edges of the anvil 5. With the central portion of the anvil elevated, the portions of the front and rear edges of the anvil 5 extending beyond the width of the tongues 10 and 10^a

10^a rest upon the upper surface of the base 1 adjacent to the slots 11 and 11^a and provide the bearing portions for the anvil 5. The reaction between the tongues and the side edges of the 5 slots 11 and 11^a maintain the anvil in proper lateral alignment during its longitudinal movement. The tongues 10 and 10^a are provided with notches in the sides thereof as indicated at 13 and 13^a. The edges of the ends of the spring 10 12 are notched inwardly as at 14 and 14^a, the notches in the spring and the notches in the tongues permitting each end of the spring to interlock with a respective tongue. The spring is of sufficient length so that when inserted between the tongues 10 and 10^a its central portion is biased in an upward direction and bears against the undersurface of the base 1.

If only two sets of deforming dies are to be used the slots 11 and 11^a are so positioned that 20 the abutment between the tongues and the rear edges of the respective slots causes an accurate positioning of one set of dies with respect to the ejection chute E while the abutment between the tongues and the forward edges of the 25 respective slots accurately aligns the other set of deforming dies. The friction caused by the spring acting between the anvil and the base is sufficient to maintain the anvil in either one of these selected positions.

30 When more than two sets of dies are to be used as indicated in Figure 2 the base adjacent to the side edges of slot 11 is provided with a plurality of teeth and grooves indicated generally at 15 and 15^a. The forward edge of the anvil 5 adjacent to the tongue 10 is provided with a downwardly facing tooth-like edge 16 (Figure 4) which registers with the teeth and grooves 15 in the base 1.

The teeth and grooves formed in the base are 40 fixed in such position relative to the sets of deforming dies that when the toothed edge 16 seats in one of the grooves in the base a selected set of deforming dies will be accurately aligned with the ejection chute E. The action of the spring 45 12 will cause the tooth-like edge 16 to slide into the bottom of one or another of the grooves formed in the base. The tooth-like edge 16 will not, under ordinary usage, rest upon the toothed part formed in the base. Thus, it is insured that 50 no matter in what manner the operator of the device moves the anvil 5 relative to the base it will automatically adjust itself in a position in which one set of deforming dies is accurately aligned.

55 To facilitate the movement of the anvil relative to the base 1, it may be provided with laterally extending finger pieces 17 and 17^a which project beyond the lateral surfaces of the housing 3 and are readily accessible to the operator.

60 In the modification shown in Figure 7, the tongues 10 and 10^a projecting through the base 1 may be threaded and a washer 18 and nut 19 may be used on each tongue to lock the anvil 5 rigidly. The anvil 5 may be adjusted by partly

loosening the nuts 19, moving it to selected position and tightening the nuts.

While constructions in which this invention may be embodied have been shown and described, it is to be understood that these constructions 5 have been selected merely for the purpose of illustration or example and that various changes in the size, shape and arrangement of the parts may be made without departing from the spirit of the invention or the scope of the subjoined 10 claims.

The invention claimed is:

1. In a stapling machine, the combination of a base, an anvil provided with two different types of elongated clenching recesses, means for supporting said anvil on said base for movement transversely of the direction of the lengths of said recesses, said means comprising downwardly extending lugs formed on said anvil operating in elongated slots formed in said base, and means 20 carried by said lugs and cooperating with said base for holding said anvil in either of its positions of adjustment.

2. In a stapling device, a base, a staple driving part, an anvil having a plurality of differently 25 acting staple deforming dies, said anvil movably mounted on said base, means coacting between said anvil and base to constrain said anvil to move longitudinally of said base and in alignment with said driving part, tooth and groove 30 means, and a spring acting to cause said tooth and groove means to move said anvils so that one of said deforming dies is in alignment with said driving part.

3. In a stapling machine, a base, an anvil slidably mounted thereon and constrained to move longitudinally thereof, inclined tooth and notch means acting to locate said anvil in different positions in relation to said base, and spring means causing said inclined tooth and notch 40 means to move said anvil into proper aligned position.

4. In a stapling machine, a base, an anvil slidably mounted thereon, elongated slots in said base, said anvil having parts cooperating with said slots and slidably therein, and means associated with said anvil to lock said anvil to said base in selected positions within the range of 45 said slots.

5. In a stapling device, a base, staple driving mechanism carried by said base, an anvil movably mounted on said base and having a plurality of different sets of clenching cavities, said anvil being constrained to move longitudinally of said base and transversely of the longitudinal lengths of said clenching cavities, inclined plane and rider means operative to cause the movement of said anvil and position the same with a respective set of clenching cavities in operative relation to said driving mechanism, and spring means cooperable with said means to maintain said anvil in a selected position.

WILLIAM G. PANKONIN.
